UNITED STATES PATENT OFFICE.

CHARLES W. JONES, OF OAKLAND, CALIFORNIA.

STEAM-TURBINE.

1,307,864.

Specification of Letters Patent. Patented June 24, 1919.

Application filed March 19, 1918. Serial No. 223,286.

To all whom it may concern:

Be it known that I, CHARLES W. JONES, a citizen of the United States, residing at Oakland, in the county of Alameda and 5 State of California, have invented certain new and useful Improvements in Steam-Turbines, of which the following is a specification.

This invention relates to axial flow turbines of the type having two oppositely rotating rotors one of which incloses the other.

The invention has for its principal objects to provide an apparatus of the type above wherein the construction and arrangement 15 of the rotors materially simplifies the turbine enabling the same to be cheaply constructed and readily assembled or dismounted; one wherein an improved arrangement for balancing the thrust on the respective rotor shafts is provided, thus reducing the losses due to friction to a minimum; one wherein the steam flow is supplied at various points and including means whereby the steam flow at any desired point 25 may be reduced or increased when it is desired to reduce or increase the speed of the rotors.

With the above mentioned and other objects in view the invention consists in the 30 novel construction and combination of parts hereinafter described illustrated in the accompanying drawings, and set forth in the claim hereto appended, it being understood that various changes in the form, proportion, size and minor details of construction 35 within the scope of the claim may be resorted to without departing from the spirit or sacrificing any of the advantages of the invention.

40 To more fully comprehend the invention reference is directed to the accompanying drawings, wherein,

Figure 1 is a diagrammatic view of the preferred embodiment of my invention, illustrating the respective rotor shafts operating 45 an armature of an electric generator of any well known type.

Fig. 2 is a vertical section view taken centrally through the preferred embodiment of 50 my invention illustrating more particularly the form and arrangement of the oppositely rotating rotors.

Fig. 3 is a sectional view taken on line 55 3—3 of Fig. 2, viewed in the direction of the arrows.

Fig. 4 is a vertical sectional view of a

thrust bearing, one of which coöperates with each of said rotor shafts, and

Fig. 5 is a sectional view taken on line 5—5 of Fig. 4. 60

To more fully comprehend the invention reference is directed to the accompanying drawings, wherein like characters of reference designate corresponding parts, and wherein 1, indicates a hollow shell or casing preferably circular in form and provided with a removable closure plate or wall 2, secured in position thereon by the bolts 3. Within the shell or casing 1, is mounted a cylindrical rotor 4 preferably formed in 65 halves which are retained in annular formation, as in the drawing, by rings or other members 5 surrounding the periphery of the same, said rings being retained in position by suitable bolts 6. The rotor 4 is secured at one edge preferably by bolts 7, to the radial supporting web 8, carried by a shaft 9, supported by a suitable bearing 10, in one wall of the shell or casing 1, said shaft passing therethrough and preferably disposed in a horizontal plane. Concentrically 70 disposed within the rotor 4, with its peripheral surface in spaced relation to the inner surface of said rotor 4, is a second rotor 11, supported by a web or disk 12 fixed to the shaft 13, which is disposed in alinement with the shaft 9, and passes to a point exteriorly of the shell or casing 1 through a bearing 14 in the plate or wall 2. The rotors 4 and 11 are designed to revolve in opposite directions and the same rotate on respective 75 shafts 9 and 13 in directions opposite to each other.

Carried on the peripheral surface of the rotor 11, and arranged in spaced rows circumferentially thereof are the radially disposed impact vanes 15 which fall short of contacting at their outer ends with the inner surface of the rotor 4. The inner surface of the rotor 4, is provided with the inwardly extending annular rows of curved reaction blades 16, said rows being positioned intermediate said rows of blades 15, and the free ends of said respective blades falling short of contacting with the peripheral surface 100 of the rotor 11, thus, it will be apparent on the direction of live steam under pressure laterally into the space 17, between said rotors 4 and 11, that the same will act alternately on the blades of the respective rotors 110 causing said rotors to rotate in opposite directions. The space 17 between the rotors

increases toward said web 8 to permit of the expansion of the live steam prior to passing through the ports 18 in the web 8, and exhausting from the shell or casing 1 through 5 the outlets 19, thus the full expansive force of the steam is utilized in the operation of the concentrically disposed oppositely rotating rotors.

Carried on the inner face of the plate or 10 wall 2, with its inner edge lying in close proximity to the corresponding edges of the rotors 4 and 11 is an annular member 20, provided with a channel 21, communicating with one or more ducts 22, through which 15 live steam under pressure is supplied for the operation of said rotors. Carried on the edges of the respective rotors 4 and 11 lying adjacent the inner face of the annular member 20, are spaced baffle rings 23 overlapping coöperating baffle rings 24, carried by said member 20, said rings preventing the escape of steam between the edges of the rotors and the face of the member 20.

Steam under pressure supplied to the 20 channel 21 discharges into the space 17, through suitable nozzles 25, arranged at spaced intervals circumferentially of said member 21, said nozzles being disposed obliquely to the axis of rotation of said 25 shafts 9 and 13 thereby directing the steam jet issuing therefrom against the blades 15, to control the direction of rotation of said rotors 4 and 11. The steam passing through the nozzles 25 is controlled by the respective 30 valves 26, carried by a suitable mechanism, or casing 27, mounted in and passing through the plate or wall 2. An operating handle 28 is provided for independently operating the respective valves 26 to control 35 the steam supply passing through the respective nozzles 25. To reduce the pressure between the web 12 and the inner surface of the plate or wall 2, and to permit the escape of any condensation therebetween there are 40 provided one or more drain outlets 29 connecting with said space and communicating at their outer or discharge ends with the outlet 19.

Owing to the rotating of the rotors 4 and 45 11 in opposite directions due to the impact and expansion of the steam directed against the blades 15 and 16, considerable end thrust is placed on the shafts 9 and 13, the tendency of said thrust being to force said shafts in 50 longitudinally opposite directions, and to counteract or balance this thrust I provide each of said shafts preferably at a point exteriorly of the shell or casing 1, with a thrust bearing, one of which is illustrated in cross- 55 section in Fig. 4 of the drawings, and for the purposes of description the bearing is set forth as coöperating with shaft 9 and mounted on the exterior surface of the shell or casing 1, surrounding said shaft. The 60 shaft is provided at a point exteriorly of the

casing 1, with a flange 30, between which and a nut 31 threaded over said flange is secured to rotate with said shaft a circular disk 32. The disk 32 is mounted within a housing circular in cross-section and consisting of the face plate 33 and shell 34, said shell and face plate being secured together and to the wall 1 by bolts 35 passing therethrough. A suitable member 36, formed of lamination is interposed between the face 75 plate 33, and wall 1 to properly position said casing relatively to the disk 32. The disk 32 rotates with the shaft supporting same in a chamber 37, within the housing 34 and positioned within said chamber one at each 80 side of said disk, are suitable annular thrust bearings 38, of any desired type, said bearings operating on rings 39 carried by opposite sides of the disk 32, and the inner faces of the coöperating walls of chamber 37. The 85 disk 32 is capable of a slight lateral movement between the thrust bearings 38, and the outer face of said disk coöperates adjacent its periphery as at 40, with a thrust ring 41, preferably of soft metal and arranged 90 circumferentially of the outer thrust bearings 38, thus providing a chamber 42 at one side of the disk 32 within the housing 34 and within which the thrust bearing 38 is mounted. Fluid under pressure, preferably 95 oil is supplied through the valve controlled pipe 43 to said chamber 42, the pressure of said fluid within the chamber 42 under normal conditions is sufficient to receive the outward thrust exerted on said shaft 9, however when said pressure is greater than the thrust on said shaft 9, said disk 32 is forced thereby into slight spaced relation from the ring 41, permitting the escape of the oil into the chamber 37 from which it drains through 100 105 a pipe 44 into a suitable sump, not shown, to be repumped under pressure, into the chamber 42.

The thrust bearings 38 are brought into use only in case the pressure within the 110 chamber 42 should fail, as under all other conditions said pressure is sufficient to provide a fluid bearing for counteracting the outward thrust exerted on the shaft.

To insure the uniform operation of the 115 rotors and to prevent one from running wild when the other is connected to deliver power, said shafts are preferably connected as in Fig. 1 of the drawings, to the armatures of suitable generators, or said shafts may be 120 through a counter-shaft connected to rotate or deliver power to any suitable mechanism.

Having thus described my invention what 125 I claim as new is:

An axial flow turbine comprising a casing open at one side, a closure plate for closing said opening, a pair of concentrically disposed oppositely rotatable rotors mounted within said casing and supported 130

- by separate aligned shafts extending exteriorly of the casing in opposite directions, one passing through the casing wall and the other passing through said closure plate,
- 5 the peripheral edges of said rotors at the inlet side of said turbine lying in parallel spaced relation and providing between the same a fluid expansion chamber open at its opposite sides and increasing in area toward
- 10 the discharge side thereof, impact and reaction blades carried by the co-operating surfaces of the respective rotors and extending into said chamber with the ends of oppositely disposed blades overlapping, a channeled annular member carried on the inner side of said closure plate opposite the spaced peripheral edges of said rotors and lying
- 15 in close proximity to said spaced edges at the inlet side of said chamber, a plurality of independent nozzles carried by said annular member and arranged circumferentially thereof in spaced relation with their discharge ends projecting between the spaced peripheral edges of said rotor and arranged tangentially to said blades, and a valve for controlling each nozzle.

In testimony whereof I have signed my name to this specification in the presence of two subscribing witnesses.

CHARLES W. JONES.
